UNITED STATES PATENT OFFICE.

ELLIOTT D. CAMPBELL, OF SAN FRANCISCO, CALIFORNIA.

FLATIRON.

Application filed July 7, 1926. Serial No. 121,017.

This invention relates to flat irons, and more particularly to electric flat irons.

An object of my present invention is the provision of a flat iron co-extensive in length with the width of the ironing board, and which may be lifted above the ironing board by means hereinafter described when it is desired to push the iron onto the material being ironed, and so constructed that with the iron above the ironing board the former may be readily pushed forward onto the piece being ironed, without the necessity of directly lifting the iron.

With the foregoing object in view, together with such other objects and advantages as may subsequently appear, this invention resides in the construction and arrangement of parts hereinafter described and claimed, and illustrated in the accompanying drawings, in which—

Figure 1 is a perspective view of the flat iron of my invention, showing the same on a portion of an ironing board.

Figure 2 is an end view of a modification of the flat iron shown in Figure 1.

Referring to the drawings for a more detailed description thereof, it will be seen that the numeral 1 indicates an ironing board on which rests the flat iron 3 which is substantially of the same length as the width of the ironing board, so that the object to be ironed may be ironed with maximum efficiency. The flat iron is of the electrical type, that is to say, it may be heated electrically by means of any well known apparatus for that purpose. The numerals 4 and 5 indicate terminals of the electrical conductors which are underneath the casing 6 of the flat iron. The casing 6 is provided at its ends with extensions 7 to which are pivoted vertical guide rollers 8, the distance between which is slightly greater than the width of the ironing board, so that an object to be ironed if wider than the ironing board may lie between one or both of the guide rollers 8 and the sides of the ironing board. The casing 6 is preferably rounded at its lower forward edge and at its forward lower corners 9 and is pushed forward by a handle 10 extending rearwardly from the trailing side of the flat iron. A roller 12 is pivoted to projections 15 and 16 which

are secured to the casing of the iron and extend beyond the trailing side of the casing of the iron. These rollers are therefore separated somewhat from the casing. The flat iron proper is indicated by the numeral 17. After a piece to be ironed is placed on the board, the iron may be pushed onto the piece to be ironed by pushing down on the handle 10 until the weight of the iron is on the rollers 12 and the iron is raised above the piece to be ironed. The iron may then be rolled onto the piece to be ironed by virtue of the rollers 12. In the form shown in Figure 2 the rollers 12 need not be provided, as the trailing edge of the flat iron proper or of the casing or of both may be rounded.

The ironing board 1, shown in conjunction or co-operation with my improved iron is of a type wherein the sides of the board are parallel from one end of the board to the other, in order to operatively accommodate actions of the rollers 8 anywhere within the length of the board.

As shown in Figure 3, one end of the board is provided with an iron rest 18, which may be formed of metal, asbestos or any other suitable material, so as to protect the board when the iron is at rest or not in use.

I claim:

1. A flat iron provided with rollers adjacent its trailing edge, said iron being substantially co-extensive in length with the width of the ironing board on which it is used and provided at its ends with guide rollers extending downwardly, the distance between said rollers being slightly greater than the width of the ironing board.

2. A flat iron comprising a rectangularly-shaped body portion having a length equal to the width of an ironing board, a handle carried by said body portion and rollers disposed at the rear corners of said body portion, and normally being positioned above the under surface of said body, said rollers being brought into contact with the ironing board when said handle is depressed, whereby said rollers will temporarily support the body.

ELLIOTT D. CAMPBELL,
